UNITED STATES PATENT OFFICE.

DAVID NICKEL, OF MORRIS, ILLINOIS.

DESIGN FOR A HANGER.

SPECIFICATION forming part of Design No. 15,917, dated March 3, 1885.

Application filed January 20, 1885. Term of patent 7 years.

To all whom it may concern:

Be it known that I, DAVID NICKEL, a citizen of the United States, residing at Morris, in the county of Grundy and State of Illinois, have invented and produced a Design for Hangers; and I do declare the following to be a full, clear, and exact description of the design, reference being had to the accompanying drawing, and to letters or figures of reference marked thereon, which forms a part of this specification.

This design has relation to hangers; and it consists in the novel form and configuration of the casting, as hereinafter shown and described.

In the accompanying drawing, the hanger is shown having the parallel transverse bars A A at its upper portion, said bars being connected at their upper edges by the arches B B, which are bounded by the outwardly-extending ribs C C. These ribs continue downward along the face of the front transverse bar and along the lateral edges of the vertical connecting-bars D D, which extend downward

to the annular lower portion, E, of the hanger. 25 This lower portion is circular, and has a large central opening, F. Around the exterior of the annular portion E extends a marginal rib or bounding-flange, G, which joins the lower ends of the vertical portions of the ribs C C, 30 and around the interior margin which bounds the opening F a bounding-flange, H, is provided.

What I claim, and desire to secure by Letters Patent, is—

The design for hangers, consisting of the parallel transverse bars having laterally-ribbed arches, and the lower annular portion joined thereto by vertical bars having lateral ribs continued from the ribs of the arches and joining the marginal rib of the annular portion, as shown and described. 40

In testimony whereof I affix my signature in presence of two witnesses.

DAVID NICKEL.
